UNITED STATES PATENT OFFICE.

PHILIP SPITZENBERG, OF NEW YORK, N. Y.

SIPHON-HEAD.

No. 806,593.

Specification of Letters Patent.

Patented Dec. 5, 1905.

Application filed March 6, 1905. Serial No. 248,534.

To all whom it may concern:

Be it known that I, PHILIP SPITZENBERG, a citizen of the United States, and a resident of the borough of Brooklyn, in the city of New York, county of Kings, and State of New York, have invented certain new and useful Improvements in Siphon-Heads, of which the following is a specification, reference being had therein to the accompanying drawings, 10 which form a part thereof.

My invention relates to siphon-heads, and more particularly to the valve mechanism thereof.

As now commonly made the head is cast 15 with a dividing-partition just below the spout, a valve-seat being subsequently turned and finished on the lower side of said partition, it being found impossible to cast this seat sufficiently accurately to avoid the necessity for 20 this finishing process. In case of wear on said seat it is in this type of head necessary to send the siphon to the factory or shop to refinish said seat, and when this wear is too great it becomes necessary to replace the entire head-casting. In this form of head it is 25 necessary in assembling to insert the valve-stem, its spring, and packing on one side of said partition, a removable cap being required for this purpose. The labor of assembling is 30 also materially increased by the necessity for depressing the valve-spring in order to adjust the lever-handle controlling same. A further difficulty encountered is that incidental to properly fitting the cap to the head-casting.

35 The main object of the invention is to produce a siphon-head in which this dividing-partition is dispensed with and the valve-seat is separable from said casting to permit the substitution of a new valve-seat for a worn one.

40 A further object is to provide an article of this character wherein the valve-seat may be cast ready for use without the necessity for subsequently finishing same.

A still further object is to provide such an 45 article wherein the valve-stem, its spring, and packing may be inserted in the head-casting from the bottom, thus obviating the necessity for a removal of the top cap and facilitating the assembling of the device or its repair.

50 A still further object is to so construct and arrange the various parts of said head as to cause the act of attaching the head to a bottle to pack on both sides of the valve-seat to confine the liquid discharged therethrough 55 within the required limits; and a still fur-

ther object is to provide a siphon-head which may be inexpensively manufactured and the parts of which most subject to wear may be replaced without material expense, such as is incidental to forwarding bottles to the shop 60 or factory.

The invention consists, primarily, in the combination, with a head-casting having an interior chamber opening downwardly and a spout communicating therewith and means 65 whereby said head-casting may be attached to a bottle and placed in communication therewith through the siphon-tube, of a valve-seat block seated in said chamber and separable from said head-casting, said block presenting 70 downwardly a face whereby it is held in place through said means and having a way therein whereby communication is established between said tube and said spout, a valve-stem, a normally closed valve controlled thereby, 75 means whereby said valve-stem may be actuated, and packing for said block, and in such other novel features of construction and arrangement of parts as are hereinafter set forth and described, and more particularly pointed 80 out in the claims hereto appended.

Referring to the drawings, Figure 1 is an elevation of a siphon-head embodying my invention applied to the upper part of an ordinary type of bottle. Fig. 2 is a vertical section thereof. Fig. 3 is an elevation of the valve mechanism detached from the head-casting, and Fig. 4 is a vertical section thereof.

Like letters refer to like parts throughout the several views.

In the accompanying drawings, *a* indicates the upper part of an ordinary siphon-bottle, the neck of which has an exterior lip *a'*. A siphon-head is secured to said bottle by any desired means, that usually employed being 95 a split screw-threaded ring *b*, adapted to engage the said lip *a'* and coöperate with screw-threads in the interior of the lower part of the siphon-head, as shown in the drawings. A glass tube *c* is suspended within the bottle by 100 means of a funnel-shaped top *c'*, attached thereto and having a flange *c''*, between which and the top of the neck of the bottle is an annular gasket or packing-ring *d*.

The foregoing arrangement of parts is that 105 now generally employed, and it is not my intention to claim such, this invention residing more particularly in the detailed construction of the siphon-head alone or in combination with the heretofore-described combination of 110

parts for attaching same or any other desired combination of parts serving the same purpose.

The siphon-head embodies a head-casting *e*, having therein a chamber adapted to receive the valve mechanism, the valve-seat block, and the means actuating the valve. Said head-casting in its preferred form presents within said chamber two substantially parallel annular shoulders *e'* *e''* of different diameters, a fulcrum *e*³ for the lever-handle *f*, and a way *e*⁴, in which said handle moves. This chamber opens downwardly and is closed at the top. A spout *g*, as ordinarily now employed, is carried by said head and communicates with the chamber therein. Preferably this head is cast in a single piece, the absence of a valve-seat partition below the entrance to the spout permitting this. This production of the head-casting at a single operation is in the interest of economy; but it is apparent that, if desired, it may be made in several parts and subsequently assembled for use in connection with the other features of my invention.

The valve mechanism embodies a valve-seat block consisting of the base *h*, the lower face of which is provided with a channel forming a central valve-seat *h'* and a rim *h''*, both of which are downwardly projected, a body *i* surmounting said base and fitting fairly snugly within that portion of the chamber within the head-casting below the shoulder *e'*. This body is of smaller diameter than the base, the upper face of which latter extends below the shoulder *e''*. The said body is surmounted by a gasket or packing-ring *i'*, preferably of soft rubber, which packs the chamber above the said block. To permit the passage of water or other liquid through said block to the spout, I provide a continuous way *i''* therein and also a channel exterior to said body, as *i''*. A puppet-valve *k* bears against the valve-seat *h'*, normally closing the way *i''*. This valve is provided with a packing *k'*, preferably of soft rubber, and the metallic body thereof is provided with fins *k''* or other means facilitating the assembling of the valve mechanism.

The valve-stem *l* is attached to the valve *k*, preferably by means whereby said valve is separable from said stem, as co-operating screw-threads on said parts, thus admitting of the replacement of the valve-block when worn. Said stem *l* is mounted in a way in the upper part of the body *i* of said block, the packing-ring *i'* serving to also pack this stem. A head *m*, provided with a central top flange *m'*, surmounts said stem, the sides of said head fitting and moving in the upper part of the chamber within said head-casting and serving as an upper seat for the valve-spring *n*, the other end of which spring is seated on a washer *o*, resting upon the packing-ring *i'*.

The handle *f* is provided with a recess adapted to engage the flange *m'* and a protruding

end adapted to rest upon the fulcrum *e*³, the inner end thereof being fitted to the way *e*⁴.

In assembling the device the spring *n* is slipped over the valve-stem *l*, the washer *o*, the gasket or packing-ring *i'*, and the valve-seat block also being mounted on said stem. These parts when so assembled are held in a suitable keeper, and the valve *k* is then attached to the bottom of the stem by being screwed thereon to an extent to hold all these parts in relation to each other and so tension the spring *n* as to normally hold the said valve *k* against the seat *h'* on the base *h* of the valve-seat block, the channel forming said seat permitting an automatic adjustment of said valve to said seat to compensate for any wear on the said seat or on the packing-ring *k'* to said valve. Thereupon the lever-handle *f* is inserted through the way *e*⁴ with its protruding end resting upon the fulcrum *e*³, and the valve mechanism assembled as heretofore described is forced into the chamber in the head-casting *e* until the packing *i'* engages the shoulder *e''*. Owing to the necessity for the packing-ring *i'* being a fairly-tight fit, some difficulty may be experienced in so forcing said valve mechanism to place; but this is largely avoided by slightly tapering said ring. When once placed, however, the friction between this ring and the head-casting is sufficiently great to hold the valve mechanism in place while applying the entire head to the bottle.

Preparatory to attaching the head to the bottle the rubber packing-ring *d* is placed on the top of the bottle and the siphon-tube *c* is passed therethrough until the flange *c'* of the funnel-shaped top *c*' thereof rests upon said ring, thus suspending the said tube within the bottle in the proper position, or, if desired, the said ring may first be placed with relation to said flange *c'*. The split ring *b* is then fitted below the lip *a'* and the head-casting screwed to place thereon. As will readily appear from the showing of Fig. 2 of the drawings, the flanged top *c*' enters the channel about the valve-seat *h'*, the rim bearing upon the gasket or packing-ring *d* and so expanding same as to pack the valve mechanism in a manner to permit the liquid under pressure to pass through the way *i''* only. The valve *k* projects into the funnel-shaped top *c*', wherein it is free to move to open said way *i''*. This same operation forces the valve-seat block upward, so as to cause the shoulder *e'* to press against and expand the gasket or packing-ring *i'* in a manner to pack above said block and also about the valve-stem *l*. It is apparent that, if desired, the shoulder *e''* need not be perfectly fitted with relation to the base of the valve-seat block, the upper shoulder *e'* being alone sufficient to accomplish the desired result.

The tension of the spring *n* need not be heavy, as the function of this spring is merely to restore the valve *k* to its seat, the normal

pressure within the bottle being sufficiently great to hold said valve upon said seat so as to prevent leakage. The valve is opened by merely pressing the lever-handle f , which in turn forces the valve-stem l and the valve k downwardly against the tension of the spring n until the way i^2 is opened, whereupon water under pressure passes through said way to the space about the valve-seat block in the channel i^3 and the spout g .

By reason of the construction and arrangement of the valve-seat block it may be accurately cast without the formation of flaws or blow-holes in or about the valve-seat, thus obviating the necessity for facing or otherwise finishing said seat. If wear does occur upon this part or upon any of the packings, it will be observed that the entire valve mechanism may be removed, new parts substituted for the worn parts, and the renovated valve mechanism replaced without the necessity for machine-work thereon, which would require the shipment of the siphon-head to the shop or factory; and, furthermore, this replacement of worn parts may be accomplished without weakening or damaging the head-casting in any way whatsoever, thus limiting the loss through wear to minor and inexpensive parts which may readily be replaced.

I believe it to be broadly new in a siphon-head to provide a valve-seat block separable from the head-casting, and it is my intention to claim such broadly.

While in the accompanying drawings I have shown the various parts as being cylindrical, it is apparent that so long as the valve mechanism conforms to the chamber within the head-casting in such particulars as to provide a suitable packing thereof the contour of these parts is immaterial.

Having described my invention, what I claim as new, and desire to have protected by Letters Patent, is—

1. In a siphon-head, the combination with a head-casting having an interior chamber opening downwardly, a spout communicating therewith, and means whereby said head may be attached to a bottle and placed in communication therewith through the siphon-tube, of a valve-seat block arranged in said chamber and separable from said head-casting, said block presenting downwardly a face whereby it is held in place through said means and having a way therein whereby communication is established between said tube and said spout, a valve-stem, a normally closed valve controlled thereby, means whereby said valve-stem may be actuated and means packing said block.

2. In a siphon-head, the combination with a head-casting having an interior chamber opening downwardly, a spout communicating therewith, and means whereby said head may be attached to a bottle and placed in communication therewith through the siphon-tube,

of a valve-seat block comprising a base having a channel in the under face thereof forming a valve-seat, and a downwardly-presented rim whereby said block is held in place through said means, and a body portion, arranged in said chamber and separable from the head-casting, said block having a way therein whereby communication is established between said tube and said spout, a valve-stem, a normally closed valve for said seat, controlled by said stem, means whereby said valve-stem may be actuated, and a packing above said body.

3. In a siphon-head, the combination with a head-casting having an interior chamber, a spout communicating therewith, and means whereby said head may be attached to a bottle and placed in communication therewith through the siphon-tube, of a valve-seat block comprising a base having a channel in the under face thereof forming a valve-seat and a rim, and a body portion, arranged in said chamber and separable from the head-casting, said block having a way therein whereby communication is established between said tube and said spout, a valve-stem having an enlarged head, a valve for said seat controlled by said stem, a spring disposed between said body and said enlarged head whereby said valve is normally closed, means whereby said valve-stem may be actuated, and a packing above said body.

4. In a siphon-head, the combination with a head-casting having an interior chamber, a spout communicating therewith, and means whereby said head may be attached to a bottle and placed in communication therewith through the siphon-tube, of a valve-seat block comprising a base having a channel in the under face thereof forming a valve-seat and a rim, and a body portion, arranged in said chamber and separable from the head-casting, said block having a way therein whereby communication is established between said tube and said spout, a valve-stem, having an enlarged head, a valve for said seat controlled by said stem, a gasket or packing-ring seated on the top of said body, a spring disposed between said gasket or ring and said enlarged head whereby said valve is normally closed and means whereby said valve-stem may be actuated.

5. In a siphon-head, the combination with a head-casting having an interior chamber, a spout communicating therewith, and means whereby said head may be attached to a bottle and placed in communication therewith through the siphon-tube, of a valve-seat block comprising a base having a channel in the under face thereof forming a valve-seat and a rim, and a body portion, arranged in said chamber and separable from the head-casting, said block having a way therein whereby communication is established between said tube and said spout, a valve-stem, a normally closed valve

- closed valve for said seat removably attached to said stem and controlled thereby, means whereby said valve-stem may be actuated, and a packing above said body.
- 5 6. In a siphon-head, the combination with a head-casting having an interior chamber, a shoulder therein, a spout communicating with said chamber below said shoulder, and means whereby said head may be attached to a bottle and placed in communication therewith through the siphon-tube, of a valve-seat block seated in said chamber below said shoulder and separable from said head-casting, said block having a way therein whereby communication is established between said tube and said spout, a valve-stem, a normally closed valve controlled thereby, means whereby said stem may be actuated, and a gasket between said block and said shoulder.
- 10 7. In a siphon-head, the combination with a head-casting having an interior chamber, a shoulder therein, a spout communicating with said chamber below said shoulder, and means whereby said head may be attached to a bottle and placed in communication therewith through the siphon-tube, of a valve-seat block comprising a base having a channel on the under side thereof forming a valve-seat and a rim, and a body, said block having a way therein whereby communication is established between said tube and said spout, a valve-stem, a normally closed valve for said seat controlled by said stem, means whereby said valve-stem may be actuated, and a gasket between said body and said shoulder and about said stem.
- 15 8. In a siphon-head, a valve mechanism comprising a valve-seat block having a way therein and presenting downwardly a rim whereby said block is held in place through the means attaching the head to the bottle, a valve-stem carried thereby, a valve on said stem, means whereby said valve is normally held closed, and a packing-ring mounted on said block and about said stem.
- 20 9. In a siphon-head, a valve mechanism comprising a valve-seat block having a way therein and presenting downwardly a rim whereby said block is held in place through the means attaching the head to the bottle, a valve-stem carried thereby, a valve removably attached to said stem, means whereby said valve is normally held closed and a packing-ring mounted on said block and about said stem.
- 25 10. In a siphon-head, a valve mechanism comprising a valve-seat block consisting of a base having a channel on the under side thereof forming a valve-seat and a rim, said block having a way therein opening through said valve-seat, and a body, a valve-stem carried in said block and passing through said way, an enlarged head on said stem, means thereon whereby said stem may be actuated, a valve for said seat removably attached to said stem, a packing-ring mounted on said body and about said stem, and a spring mounted between said packing and said enlarged head whereby said valve is normally closed.
- 30 11. In witness whereof I have hereunto affixed my signature, this 24th day of February, 1905, in the presence of two witnesses.
